UNITED STATES PATENT OFFICE.

HOLMAN K. WHEELER, OF LYNN, MASSACHUSETTS, ASSIGNOR OF ONE-HALF
TO GEORGE J. CARR, OF SAME PLACE.

PENCIL-SHARPENING MACHINE.

SPECIFICATION forming part of Letters Patent No. 620,862, dated March 7, 1899.

Application filed April 7, 1898. Serial No. 676,753. (No model.)

To all whom it may concern:

Be it known that I, HOLMAN K. WHEELER, of Lynn, county of Essex, Commonwealth of Massachusetts, have invented certain Improvements in Pencil-Sharpening Machines, of which the following, read in connection with the accompanying drawings, is a specification.

This invention has for its object to provide a machine for sharpening pencils automatically.

In the drawings, Figure 1 is an elevation of the longitudinal vertical section of a machine embodying this invention. Fig. 2 is an end elevation of the machine. Fig. 3 is a plan view of the machine. Fig. 4 shows in perspective the inner member of the pencil-holding chuck. Fig. 5 is a similar view of the cutter-holding shaft referred to hereinafter. Fig. 6 shows a section of the cutter enlarged.

The machine comprises a frame or body part 2, wherein is a chamber 3, adapted for receiving the cutter 10, with space above the cutter to be occupied by the pencil and a space below the cutter for receiving the chips and lead-dust removed by the sharpening operation. At the bottom of the chamber 3 is a plate 5, held in place by the ribs 6, whereon the chips are collected, and it may be removed by the workman at will.

The sleeve-shaft 7 has the flanged cap 8 firmly brazed to one end thereof (see Fig. 5) and is screw-threaded at the other end for receiving the screw-threaded sheave 9, and it is designed for rotating the cutter 10. To this end the cutter 10 is placed upon the sleeve 7 in bearing with the inner end face of the cap 8 and is followed up by the collar 12, after which the sheave 9 is introduced and screwed forward to firmly clamp the cutter 10 in place between the collar 12 and cap 8. Said collar and cap, being supported for rotation in the bearings formed therefor in the frame part 2, will in rotating cause rotation of the cutter 10.

The pencil-holding chuck comprises an inner member 14, an outer member 16, and a spiral spring member 18, which spring 18, being contracted between the inner and outer members, normally operates to force a movement thereof longitudinally one with rela-

tion to the other. The inner member 14 is formed, preferably, of thin tubular metal, and for a portion of its length is divided into quarters by longitudinal slots 20, whereby are formed the fingers 21, adapted for movement inwardly when pressed upon. On the finger parts 21 are projections 22, which may be conveniently formed by forcing the metal outwardly and upwardly at such places. These projections 22 are designed for co-operation with the beveled inner-wall faces 24 of the outer chuck member 16, all this to the end that longitudinal movement of the inner and outer members effected by the spring 18 will operate the fingers inwardly for clamping and holding the pencil. Obviously a relative movement of the members 14, 16 in the direction which operates the contraction of the spring 18 will give way for the fingers to move outwardly and allow for the removal or the introduction and adjustment of the pencil, as desired. The outer chuck member 16 has the circumferential groove 28, wherein is entered the forked end of the frame projection 30, while its foremost end bears normally on the frame part at the point 32. This arrangement operates to support the chuck for movement rotatively, and it further allows of longitudinal tilting movements of the chuck on the forked projection 30, as may be desired for adjusting the pencil and feeding it to the cutter. Rotation of the chuck is effected by a belt 34, which to that end travels from the sheave 9 over the chuck member 16. This belt preferably is made to consist of a ring or round band of rubber, which is strained over the parts under a tension which allows it to yield for the desired tilting movement of the chuck, and it normally operates to hold the chuck from being displaced during rotation and gradually depresses the foremost end of the chuck, as is required for feeding the pencil to the cutter.

Motion is primarily imparted to the sleeve 7 through the medium of a motor-shaft 40, which may be economically formed of two lines of round wire twisted spirally, one about the other in duplicate, as is shown in Fig. 1. Thereby each of said wires is made to form an inclined rib extending spirally the length of the shaft. Through the end of cap 8 are

bored two intersecting circular holes 42 43 of a diameter equal to the diameter of said wire. Into the opening thus made is introduced the said motor-shaft, which, being held against rotation, is reciprocated longitudinally, the result being to cause revolution of the sleeve 7, and consequently the cutter and pencil-holding chuck, first in one direction as the shaft goes forward and then in a reverse direction as the shaft goes backward.

It remains to describe the cutter, which, it may be understood, is a round block of tool-steel having its peripheral face beveled toward one end. On this beveled circular face are set the cutting members, which may be formed by striking up the surface material, as in the art of file-cutting. Preferably the surface is worked over once with the cutting-tool supported at one inclination, as indicated by dotted lines, Fig. 6, and then worked over a second time with the cutting-tool supported at the obverse inclination, as indicated by full lines in Fig. 6. The result is to form cutting members of different inclinations. Those inclined one way operate in cutting the pencil while the cutter revolves in one direction; but a reverse rotation of the cutter calls into action the cutting members having the reverse inclination. The result is to effect a cutting of the pencil during each rotation of the cutter; but another result is that during the reverse movement the cutter members are cleared of the chips which may have lodged therein during the forward cutting movement. The shaft is provided with a handle 60 for convenience in operating, and preferably, too, it is concealed in part by the shell or housing 62.

The relative arrangement of the cutter and pencil-holding chuck is made such that in the beginning the pencil shall rest upon the face of the cutter, the chuck being then raised from the bearing 32 against the tension of belt 34; but as the cutting progresses the belt 34 draws downwardly and continuously feeds the pencil to the cutter until the chuck member 16 rests upon the bearing 32, at which time the pencil will have been fully sharpened and pointed, and this bearing 32 will operate to prevent overworking and possibly damaging the perfected point.

I claim—

1. A machine for sharpening pencils comprising a cutter adapted for movement in opposite directions and provided with means for cutting in both of said directions, combined with actuating mechanism adapted for moving the cutter alternately in one and then in the other of said directions, substantially as described.

2. A machine for sharpening pencils comprising a cutter adapted for movement in opposite directions and provided with means for cutting in both of said directions, combined with means for moving the cutter alternately in one, and then in the other of said directions and means for holding and means for

feeding the pencil to the cutter, substantially as described.

3. A pencil-sharpening machine comprising a cutter adapted for movement in opposite directions, and having provisions for cutting in both of said directions, combined with means for holding the pencil, and means for rotating and feeding the pencil to the cutter and means for moving the cutter alternately in one and then in the other of said directions, substantially as described.

4. A machine for sharpening pencils, comprising a cutter adapted for movement rotatively in opposite directions and the cutter having provision for cutting in both of said directions combined with means for holding and means for feeding the pencil to the cutter and means for moving the cutter alternately in one and then in the other of said directions, substantially as described.

5. A machine for sharpening pencils, comprising a cutter adapted for movement rotatively in opposite directions and the cutter having provision for cutting in both of said directions combined with means for holding and means for feeding the pencil to the cutter and means for moving the cutter alternately in one and then in the other of said directions, and means for simultaneously rotating the pencil, substantially as described.

6. A machine for sharpening pencils comprising a cutter a shaft and means to rotate the shaft a pivoted pencil-holding chuck and an elastic connection between the said shaft and chuck wherethrough motion is transmitted for rotating the chuck, said connection operating also for feeding the pencil to the cutter, substantially as described.

7. A machine for sharpening pencils, comprising a cutter a shaft, and means for rotating the shaft a pivoted pencil-holding chuck and a belt connection between the shaft and chuck composed of rubber or a similarly-elastic material wherethrough motion is transmitted for rotating the chuck said connection operating also for feeding the pencil to the cutter, substantially as described.

8. A machine for sharpening pencils, comprising, a shaft, a cutter supported for movement with the shaft and means for rotating the shaft said means operating normally to rotate the shaft alternately in one and then in the opposite direction combined with a pencil-holding chuck, and a connection between the shaft and chuck wherethrough motion is transmitted for rotating the chuck and means for feeding the pencil to the cutter, substantially as described.

9. A machine for sharpening pencils, comprising, a shaft, a cutter supported for movement with the shaft and means for rotating the shaft said means operating normally for rotating the shaft alternately in one and then in the opposite direction and said cutter having provision for cutting the pencil in both of said directions combined with a pencil-holding chuck and means for rotating the chuck

and feeding the pencil to the cutter, substantially as described.

10. A machine for sharpening pencils, consisting of the frame part 2, the shaft 7 supported for rotation in the frame part and carrying the cutter 10, and means for moving the shaft, the pencil-holding chuck supported for rotation on a projection of the frame part, and further adapted for longitudinal tilting 10 movement thereon whereby to carry the pencil toward and from the cutter, combined with the elastic belt connection wherethrough motion is transmitted from the shaft to the chuck and the pencil actuated toward the cutter, all 15 substantially as described.
11. A machine for sharpening pencils comprising a rotatable cutter and a rotatable holder combined with an endwise-movable motor-shaft and means wherethrough move- 20 ment of the shaft in one direction causes rotation of the cutter and holder in one direc-

tion and movement of the shaft in the other direction operates to rotate the cutter and holder in the reverse direction, substantially as described.

12. The combination with a tapering rotatable cutter, of a movably-supported pencil-holder, and means for pressing the holder toward the center, said means being resisted only by the pencil until the latter is ground 25 to the desired point.

13. The combination with a rotary pencil holder and cutter, of an elastic connection between the cutter and holder for imparting motion from one to the other, said connection 30 being such as to feed the pencil to the cutter while it is being turned.

Signed March 28, A. D. 1898.

HOLMAN K. WHEELER.
